UNITED STATES PATENT OFFICE.

FREDERICK HERBST, OF OURAY, COLORADO, ASSIGNOR OF ONE-HALF TO I. A. MARTIN AND R. W. HASKINS, OF OURAY, COLORADO.

CHARGE-FORMING DEVICE FOR INTERNAL-COMBUSTION ENGINES.

No. 872,419.

Specification of Letters Patent.

Patented Dec. 3, 1907.

Application filed April 5, 1907. Serial No. 366,508.

To all whom it may concern:

Be it known that I, FREDERICK HERBST, a citizen of the United States, residing at Ouray, in the county of Ouray and State of Colorado, have invented certain new and useful Improvements in Charge-Forming Devices for Internal-Combustion Engines, of which the following is a specification.

This invention is a charge forming device for internal combustion engines, and it includes a pump, a carbureter or mixing chamber and an auxiliary air valve; as well as associated parts to be hereinafter more particularly described.

An especial feature of the pump is that it will deliver an exact amount of the fuel at each stroke, and does not depend upon suction in the mixing chamber, or other uncertain means, but will deliver a positive amount, which however may be varied by adjusting devices to be described.

The invention is illustrated in the accompanying drawings, in which

Figure 1 is a side elevation of the device. Fig. 2 is a central vertical section with the pump plunger in lowered position. Fig. 3 is a similar view with the pump plunger lifted. Fig. 4 is a vertical section at right angles to Figs. 2 and 3. Fig. 5 is a horizontal section on the line 5—5 of Fig. 2. Fig. 6 is a detail in section on the line 6—6 of Fig. 2.

Referring specifically to the drawings, A indicates the body of the carbureter or mixing chamber. This is an upright hollow cylinder having in the bottom thereof a series of air inlet openings W covered by a check valve J, which opens upwardly at the inspiration of the engine and is at other times held closed by its weight and by a spring K coiled around its stem. At the top the cylinder is connected to a pipe or fitting V which has a lateral outlet X to the engine.

Located centrally within the cylinder A is an oil or fluid fuel chamber B, which is held in the center and supported in the body by three wings O fitting and fixed within the cylinder. The chamber or vessel B receives the fluid fuel through a pipe T which is provided, outside the carbureter, with an air chamber S to cushion the stroke of the pump. The chamber B is closed at the bottom by a

removable screw plug b which also has a bore j forming a guide for the stem of the valve J.

In connection with the vessel B, a pump is formed by means of a plunger C and a sleeve D. The plunger and sleeve work through a bushing v in the top of the pipe fitting V and also through a collar at the top of the vessel B. The sleeve D fits over the reduced stem of the plunger C, and the head of the plunger, 60 and the sleeve, are of the same diameter, and they work at a snug fit through the collar or opening at the top of the vessel B.

The sleeve D has a limited and adjustable sliding movement upon the stem of the plunger, between the shoulder Y at the head of the plunger and a collar F at the top of the stem thereof. The collar F is loose on the stem of the plunger, but is retained in position by a key f, which works in a groove in the stem, and by an adjusting nut G screwed on the end of the stem. The nut is held at adjustment by a spring detent E which is fixed to the collar F and engages the knurled rim of the nut. The upper end of the sleeve 75 D is fixed to the upper cross piece M of a working frame, by means of jam nuts I. This frame has also a lower cross piece M', and connecting rods M² fastened to the cross piece by nuts H. The connecting rods M² 80 work through holes in ears a projecting from opposite sides of the casing A, and the lower cross piece M' has ears N for the attachment or connection of the frame to a connecting rod or other reciprocating part of the engine, 85 whereby the pump is operated.

In the fitting V, opposite to the outlet X to the engine, is an auxiliary air valve consisting of a plug P the outer end of which has holes p controlled by a turning disk R having 90 holes r which may be registered or not registered with the holes p. The plate R is held in position by a screw R' and nuts R². At the inner end the plug has a check valve Q, opening inwardly.

Located within the vessel B are a pair of opposite spring fingers having friction pieces L which embrace the head of the plunger C and serve to prevent any movement thereof except when positively operated. Extending across the chamber A, just below the collar of the vessel B, is a gauze diaphragm Z,

to distribute the oil or other fluid fuel delivered by the pump so that it may be readily taken up by the air flowing through the chamber.

5 In operation, the sleeve D is reciprocated by means of the working frame, and its movement carries with it the plunger C. On the up stroke, the sleeve is first lifted on the stem of the plunger to the extent permitted 10 by the adjusting nut G and collar F, and this produces a space between the lower end of the sleeve and the shoulder at Y. The size of this space governs the amount of the feed, and is capable of variation by adjustment of 15 the nut G. On the lift of the sleeve, the oil or other fluid fuel in the vessel B fills the said space, and continued up lift of the sleeve and plunger carries the same above the top of the vessel B, and the oil or other fluid fuel carried up in said space at Y then flows out onto 20 the gauze Z, being positively discharged by the ensuing down stroke of the sleeve D, which first strikes the shoulder Y and then pushes the plunger down into the vessel B for the 25 next operation. The friction pieces L serve to prevent movement of the plunger C except when positively actuated by the sleeve D.

The operation of the pump is so timed that the fluid will be discharged onto the gauze at 30 the suction stroke or inspiration of the engine, which draws air up through the holes W and chamber A where it vaporizes the oil or other fluid fuel on the diaphragm Z, and the mixture passes through the outlet X 35 to the engine. The auxiliary air valve may be put in or out of action by turning the plate R one way or the other, and when the holes p and r are registered an auxiliary supply of air is drawn in through said holes and 40 through the check valve Q. This auxiliary valve is useful at high speeds.

It will be seen that after adjustment the same amount of oil or other fluid fuel is positively delivered at each stroke of the pump, 45 the volume thereof being that contained in the annular space between the lower end of the sleeve D and the shoulder Y, and the size of this space is regulated by adjustment of the nut G. It will be understood that the 50 vessel B is maintained full of oil or other fluid fuel at all times.

I claim:

1. The combination of a charge-forming chamber, and a fuel pump-vessel and its 55 plunger located within the chamber and arranged to discharge thereinto, the vessel being spaced on all sides from the chamber, through which space the charge is drawn.

2. The combination of a charge-forming 60 chamber, a fuel pump-vessel and plunger located within the same, and a perforated dia- phragm extending across the chamber under the discharge from the pump, the chamber

having an air inlet below said diaphragm and an outlet above the same.

3. The combination of a charge-forming chamber having an air inlet at the bottom and a charge outlet at the top, an oil or other fluid fuel pump vessel supported within the chamber, and a pump plunger working in 70 said vessel and extending through the top of the chamber and arranged to deliver oil or other fluid fuel from the vessel into the chamber.

4. The combination of a charge-forming 75 chamber having an air inlet at one end and an outlet at the opposite end, and a liquid-fuel pump located lengthwise within said chamber and spaced from the side walls thereof forming a surrounding space or passage through which air is drawn, said pump discharging into said space and having operating means external to the chamber.

5. The combination of a charge-forming 80 chamber, a fuel pump located and discharging within the same and spaced from the walls thereof, and a supply pipe extending through the wall of the chamber and across said space and into the pump.

6. The combination of an oil or other fluid 90 fuel pump vessel, a mixing chamber surrounding the same, a plunger having a shoulder working into the vessel, and a sleeve on the plunger above the shoulder, the sleeve being movable to a limited extent, to and 95 from the shoulder, forming a space into which oil or other fluid fuel within the vessel enters at the beginning of the out stroke, and from which the oil or other fluid fuel is delivered outside the vessel and into the chamber at 100 the end of said stroke.

7. The combination of an oil or other fluid fuel pump vessel, a mixing chamber surrounding the same, a plunger having a head with a shoulder at the top, working through 105 the top of the vessel, an adjusting nut on the top of the plunger, a sleeve on the plunger, between said shoulder and nut, the sleeve being movable lengthwise on the plunger to an extent limited by said shoulder and nut, 110 means to reciprocate the sleeve and plunger, and means to prevent movement of the plunger except when positively actuated by the sleeve.

8. The combination of an oil or other fluid 115 fuel pump vessel having a hole in the top, a plunger having a head with a shoulder at the top, movable through said hole, a sleeve on the plunger above the shoulder, the sleeve and head having the same diameter and fitting the hole, and the sleeve having limited movement to and from the shoulder to form a space when the sleeve is lifted, and means to reciprocate the sleeve and plunger to raise and lower said shoulder and space out of and 120 into the vessel.

9. The combination of a cylindrical casing having a valved air inlet at the bottom and a lateral outlet near the top, an oil or other fluid fuel pump cylinder of less diameter than the casing, supported within the same between the said inlet and outlet, a plunger working through the top of the casing and into the pump cylinder, the pump having its discharge within the casing, and means to supply said pump cylinder with oil or other fluid fuel.
- 5 In testimony whereof I affix my signature, in presence of two witnesses.
